GASOLINE DISPENSER

Raymond A. Smith, Bradford Woods, Glenn W. Monigle,
Wexford, and Robert B. Gaylor, Jr., Pittsburgh, Pa.,
assignors to Symington Wayne Corporation, Salisbury,
Md., a corporation of Maryland

Continuation-in-part of design application Ser. No. 2,983,
July 8, 1966. This application Jan. 31, 1967, Ser. No.
5,636

Term of patent 14 years

(Cl. D52—2)

Fig. 1.

Fig. 4.

Fig. 3.

Fig. 5.

Fig. 2.

Fig. 6.

Fig. 7.

FIG. 1 is a front perspective view of a gasoline dispenser showing our new design;

FIG. 2 is a front elevational view thereof, the rear being a mirror image of the front shown;

FIG. 3 is an elevational view taken from one end thereof, the opposite end being a mirror image of the end shown;

FIG. 4 is a top plan view thereof;

FIG. 5 is a bottom plan view thereof;

FIG. 6 is a front perspective view of an illuminated modified form of the gasoline dispenser shown in FIG. 1;

FIG. 7 is a front elevational view of FIG. 6, the rear being a mirror image of the front shown;

FIG. 8 is an elevational view taken from one end of FIG. 6, the opposite end being a mirror image of the end shown;

FIG. 9 is a top plan view of FIG. 6; and

FIG. 10 is a bottom plan view of FIG. 6.

The dominant features reside in the portions shown in solid line.

This application is a continuation-in-part of our pending application for design patent Serial No. D. 2,983, filed July 8, 1966 and now abandoned.

We claim:

The ornamental design for a gasoline dispenser, as shown and described.
